No 2354.
Nicholas Muller's Design for Clock Case Front.

PATENTED
JUL 10 1868

15.2354

Nicholas Miller of New York, N.Y.

Letter Patent 2354. Dated July 10, 1864.

Design for a Clock Case Front.

The design referred to in these Letters Patent and making part of the same.

To all whom it may concern;

Be it known that Nicholas Miller, of the City, County and State of New York, have invented and improved Design for Clock Case Front, and do hereby declare that the following is a full, clear and exact description thereof, which will enable those skilled in the art to make and execute the same, reference being had to the accompanying drawings forming part of this Specification in which

Figure 1 represents a transverse section taken in the plane indicated by the line a, b. Figure 2

Figure 3, is a side elevation of the same.

Figure 4, is a front view of the same.

Similar letters of reference indicate corresponding parts.

This invention relates to a design for a clock case front the principal features of which are two heads A, B, which are situated near the bottom edge and which represent the heads of children exposing in each others arms; the hand C, of one of the children being shown as resting on the shoulder D, of the other. The children are covered by an ornamental cloth E, which is supported by suitable arabesques F, which continue to the corners on both sides of the heads A, B. Close above the corners the clock case front is ornamented by clusters of vine leaves G, from which emanate the grapes H, and a similar ornamentation though in a different form is applied to the top of the clock case front as clearly shown in the drawing.

Q.S. 2554

2

On the sides of the opening for the dial plate are
squared T's, which represent the shafts of pillars and
which are supported by suitable arabesques, as shown.

What I claim as new and desire to secure by Letters Patent, is,
The Design for a clock Case front as shown and described.
